UNITED STATES PATENT OFFICE.

MICHAEL TROOTNEFF AND JOHN GROMEEKO, OF SAN FRANCISCO, CALIFORNIA.

COMBINATION BATH APPARATUS.

Application filed June 22, 1925. Serial No. 38,801.

To all whom it may concern:

Be it known that we, MICHAEL TROOTNEFF and JOHN GROMEEKO, citizens of the United States, respectively, residing in the city and county of San Francisco and State of California, have invented a new and useful Improvement in a Combination Bath Apparatus, of which the following is a specification.

Our invention relates to improvements in combination bath apparatus of portable character wherein a boiler and a cold water supply tank and a furnace are mounted in connection with a common supporting frame and provided with fittings for delivering hot and cold water for bathing and washing purposes and adapted to provide dry heat and to generate steam to heat and form a steam bath within a compartment containing the apparatus.

20 The primary object of our invention is to provide an improved apparatus affording a convenient means for delivering hot and cold water and for generating steam for washing and bathing purposes.

25 Another important object is to provide an improved apparatus which may be transported as a unit from place to place and installed in any available compartment.

30 A further object is to provide an improved apparatus of the character described wherein a single furnace is utilized for heating water for bathing, for heating a bathing compartment, and for generating steam to heat and form a steam bath within a portion of such compartment.

35 Another object is to provide an apparatus which will maintain a continuous supply of hot water and which will accommodate a large number of persons.

40 A still further object is to provide an apparatus of simple and economical construction which may be easily installed and which will be efficient in operation.

45 We accomplish these and other objects by means of the improved device disclosed in the drawings forming a part of the present specification wherein like characters of reference are used to designate similar parts throughout said specification and drawings and in which,

50 Fig. 1 is a broken side elevation of the apparatus, parts being broken away and shown in section.

55 Fig. 2 is a front elevation of the apparatus.

Fig. 3 is a plan view of the apparatus.

Fig. 4 is a broken sectional detail showing the manner in which the boiler is associated with the furnace and the heat chamber.

Fig. 5 is a transverse section of the crown plate of the furnace.

Referring to the drawings the numeral 1 is used to designate in general a supporting frame preferably formed from structural iron riveted or otherwise secured together to form a rectangular skeleton frame. A furnace is formed within the lower forward portion of the frame, said furnace consisting of a fire box 2 and an ash box 3 formed by metal plates secured to the frame 1. Grate bars 4 are mounted between the fire box and the ash box. A door 6 closes the front of the fire box 2 and a door 7 closes the front of the ash box 3. A draft door 8 is preferably mounted upon the door 7 for regulating the draft upwardly through the fire box.

50 A heat chamber 9 is formed in the back of the frame 1 opposite the fire box 2 and extending upwardly thereabove, said chamber being formed by plates riveted or otherwise secured within the sides and back of the frame. A boiler 11 is mounted within the heat chamber 9, the forward side of the boiler being arranged to form the front of the heat chamber and the remaining sides of the boiler being spaced from the walls of the chamber to form smoke and heat passages around the sides and bottom of the boiler. A stack 12 is connected into the top 60 of the heat chamber.

65 A cold water supply tank 13 is mounted upon the top of the frame 1 and is connected to the boiler 11 through a pipe 14, to maintain a supply of water within the boiler to be heated. The tank 13 is filled in any suitable manner, preferably through an inlet pipe 16 provided with a valve 17 operated by a float 18 to automatically maintain the supply of water in the tank at a desired 70 level.

75 The top of the fire box 2 of the furnace is covered by a crown plate 19, the upper surface of which is corrugated as at 21 and the lower surface provided with a plurality of ribs 22, said plate extending across the entire width of the frame between the boiler 11 and the front of the frame.

80 Wash basins 23 are mounted upon the sides of the frame 1 in slightly spaced relation to the sides of the boiler. Faucets 24 and 26 are mounted above each basin 23, said

faucets being connected to the boiler 11 and the supply tank 13 through pipes 27 and 28 respectively, whereby hot or cold water may be delivered to the basin as desired.

5 Shower bath fixtures 29 are mounted at a suitable distance from the furnace and boiler and connected to the boiler and supply tank through pipes 30 and 31 provided with valves 32 whereby hot or cold water may be 10 delivered as desired.

A shower fitting 33 is mounted directly over the crown plate 19 and arranged to spray water onto said plate to generate steam, water being delivered to said fitting 15 through a pipe 34 provided with a valve 36 adapted to control the supply of water. The crown plate 19 and the fitting 33 are arranged within a steam recess 37 formed by a vertical plate 38 secured across one 20 side of the frame between the chamber 9 and the front of the frame and a horizontal plate 39 extending between the top of the chamber 9 and the front of the frame 1.

A guard strip 41 is mounted around the 25 sides and back of the frame and in slightly spaced relation thereto to prevent persons from coming in contact with heated portions of the apparatus, said strip being preferably made of non-conductive material provided with an insulating lining of asbestos or other suitable material.

The apparatus is arranged to be installed in any suitable room or compartment. In 30 installing the apparatus a wall or partition 42 is formed across the compartment flush with the front of the frame 1, said partition having an opening 43 formed therein to register with the front of the furnace to give access thereto. A second wall or partition 40 44 is formed across the compartment along the longitudinal side of the frame 1 opposite the plate 38, said partition being shaped to fit closely around the apparatus and to 45 fully separate the space in back of the partition 42 into two rooms upon opposite sides of the apparatus. The partition 44 is arranged along one side of the frame 1 so that the body of the furnace and the boiler will be contained within the room upon one 50 side of the partition while the steam recess 37 will communicate with the other room. The apparatus may be installed in connection with existing walls where convenient, or the partitions may be readily constructed from wall board or other material available at the time and place of 55 installation.

In operation the apparatus is set up as a unit in any available compartment. When 60 a fire is built in the furnace the crown plate 19 will be heated to a high temperature, and the heat from the fire passing through the chamber 9 and around the sides of the boiler 11 will heat the water contained in said 65 boiler. As water is drawn from the boiler

11 to the basins 23 and shower 29 additional quantities of water will be delivered by gravity from the supply tank 13 into the boiler and heated, thus maintaining a constant supply of hot water for washing and 70 bathing purposes.

In case the water within the boiler is caused to boil, the steam may pass upwardly through the pipe 14 and into the cold water tank 13 where it is condensed and the pressure within the boiler is thus relieved. The 75 water is delivered by quantity from both the boiler Fig. 1 and tank 13 to the basins and shower bath fittings.

In addition to maintaining a supply of 80 hot and cold water, the apparatus provides a means for generating steam to form a steam bath. This is accomplished by turning a spray of water onto the heated crown plate 19, the water being instantly converted 85 to steam within the recess 37 from which it passes freely into the portion of the compartment into which the recess opens. The plate 19 is provided with corrugations 21 upon its upper surface in order to increase 90 the surface from which the spray may be vaporized and to form troughs to retain water, while the under surface of the plate is provided with ribs 22 in order to increase 95 the quantity of heat which will be absorbed by the plate from the furnace. By regulating the amount of water sprayed onto the plate 19, the quantity of steam generated and liberated into the room and the temperature of the room may be effectively regulated. The steam is excluded from the room upon the opposite side of the partition 44 by said partition 44 and the plates 38 and 39.

The heat from the furnace and from the 105 boiler and heat chamber effectively heats the portion of the compartment opposite the steam room with a dry heat.

The apparatus is constructed, as above described, in a single unit which is made 110 of a size adapted to be transported from place to place and installed in any available compartment where required. The device is thus made particularly useful for construction camps and for army purposes where 115 relatively large numbers of men are quartered at places relatively remote from modern facilities and for periods too short to warrant the construction of permanent bath houses and the like. For such purposes 120 our device may be readily loaded upon a truck and transported from place to place and set up wherever convenient, and when installed affords the convenience of a steam 125 bath as well as affording hot and cold water for washing and bathing purposes, and at the same time heats the compartment within which it is installed for the comfort of the users.

The specific details of construction are of 130

course subject to modification in various manners without departing from the spirit of our invention. We therefore do not wish to restrict ourselves to the specific details of 5 construction as shown in the drawings, and described in the present specification, but desire to avail ourselves of all modifications which may fall within the scope of the appended claims.

10 Having thus described our invention what we claim as new and desire to secure by Letters Patent is,

1. A combination bath apparatus comprising a furnace adapted to be installed within a compartment; a boiler mounted in connection with the furnace and arranged to be heated thereby; a cold water supply tank mounted above the boiler to maintain a supply of water therein to be heated; 20 pipes connected to the boiler and the supply tank for delivering water therefrom for washing and bathing purposes; a crown plate mounted above the furnace; and means for delivering water onto the crown plate 25 for generating steam for heating the compartment containing the apparatus, said steam being liberated within the compartment to form a steam bath.

2. A combination bath apparatus comprising a furnace adapted to be installed within a compartment; a boiler mounted in connection with the furnace and arranged to be heated thereby; a cold water supply tank mounted above the boiler to maintain a supply of water therein to be heated; 30 pipes connected to the boiler and the supply tank for delivering water therefrom for washing and bathing purposes; a crown plate mounted above the furnace; and means for delivering water onto the crown plate 35 for generating steam for heating the compartment containing the apparatus, said steam being liberated within the compartment to form a steam bath; and partitions 40 arranged to exclude the steam from one side of the compartment.

3. A combination bath apparatus comprising a furnace adapted to be installed within a compartment; a boiler mounted in connection with the furnace and arranged to be heated thereby; a cold water supply tank mounted above the boiler to maintain a supply of water therein to be heated; 50 wash basins mounted adjacent the furnace; shower bath fittings mounted within the compartment; pipes connected between the boiler and supply tank and basins and shower fittings for delivering hot and cold water thereto for washing and bathing purposes; 55 a crown plate mounted above the furnace to be heated thereby; and means for delivering water onto said crown plate for generating steam for heating the compartment containing the apparatus, said steam being liberated within the compartment to form a steam bath; and partitions 60 arranged to exclude the steam from one side of the compartment.

steam being liberated within the compartment to form a steam bath. 65

4. A combination bath apparatus comprising a furnace adapted to be installed within a compartment; a boiler mounted in connection with the furnace and arranged to be heated thereby; a cold water supply tank mounted above the boiler to maintain a supply of water therein to be heated; wash basins mounted adjacent the furnace; shower bath fittings mounted within the compartment; 70 pipes connected between the boiler and supply tank and basins and shower fittings for delivering hot and cold water thereto for washing and bathing purposes; a crown plate mounted above the furnace to be heated thereby; and means for delivering water onto said crown plate for generating steam for heating the compartment containing the apparatus, said steam being 75 liberated within the compartment to form a steam bath; and partitions arranged to exclude the steam from one side of the compartment. 80

5. A combination bath apparatus comprising a furnace adapted to be installed within a compartment; a boiler mounted in connection with the furnace to be heated thereby; a cold water supply tank mounted above the boiler to maintain a supply of water therein to be heated; wash basins 90 mounted adjacent the furnace; shower bath fittings mounted within the compartment; pipes connected between the boiler and supply tank and the basins and shower fittings for delivering hot and cold water 95 thereto for washing and bathing purposes; a crown plate mounted above the furnace to be heated thereby; means for delivering water onto said crown plate for generating steam for heating the compartment containing the apparatus, said steam being liberated within the compartment to form a steam bath; and a partition extending across the compartment and connected along one side of the apparatus to form separate rooms 100 upon opposite sides of the apparatus, and to exclude the steam from one of said rooms, one of said rooms being dry heated directly by the furnace and the other heated by the steam to form a steam bath. 110

6. A combination bath apparatus comprising a frame adapted to be installed within a compartment; a furnace mounted within the lower portion of the frame; a boiler mounted within the frame and arranged to be heated by the furnace; a cold water supply tank mounted upon the top of the frame and arranged to maintain a supply of water in the boiler to be heated; wash basins mounted upon the sides of the frame; pipes connected between the boiler and supply tank and the basins for delivering hot and cold water thereto for washing purposes; 120

- shower bath fixtures mounted within the compartment and pipes connecting said fittings with the boiler and the supply tank for delivering hot and cold water for bathing; a crown sheet mounted above the furnace to be heated thereby; and means for spraying water onto said crown sheet for generating steam to form a steam bath within the compartment.
- 10 7. A combination bath apparatus comprising a structural iron frame adapted to be installed within a compartment; a furnace mounted within the bottom of the frame and comprising a fire box and an ash box arranged below the fire box; a boiler mounted within the frame to be heated by the furnace; a cold water supply tank mounted upon the top of the frame and arranged to maintain a supply of water in the boiler to be heated; wash basins mounted upon the sides of the frame; pipes connected between the boiler and supply tank and the basin for delivering hot and cold water thereto for washing purposes; shower bath fixtures mounted within the compartment and pipes connecting said fittings with the boiler and the supply tank for delivering hot and cold water for bathing; a crown sheet mounted upon the frame and closing the top of the furnace; means for spraying water upon the crown sheet for generating steam; plates forming a steam recess around the plate and spraying means and a partition extending across the compartment and connected along one longitudinal side of the apparatus, whereby the body of the furnace and boiler will be disposed upon one side of the partition to impart dry heat to one side of the compartment said partition having an opening communicating with the steam recess whereby the steam generated upon the crown sheet will be directed into the other side of the compartment to heat the same and form a steam bath therein.
- 15 8. A combination bath apparatus comprising a structural iron frame adapted to be installed within a compartment; a furnace mounted within the forward bottom portion of the frame, said furnace being formed by plates secured in connection with the frame to form a fire box and an ash box; a heat chamber formed within upper rearward portion of the frame by plates secured upon the said frame, said chamber communicating with the rearward end of the fire box; a boiler mounted within the heat chamber, said boiler having its forward side forming the front of the heat chamber and having its remaining sides spaced from the plates forming the walls of the chamber whereby the boiler may be heated upon three sides and the bottom by heat from the furnace; a cold water supply tank mounted upon the top of the frame and connected to the boiler to maintain a supply of water therein to be heated; means for delivering water from the boiler and the tank for purposes of washing and bathing; a crown sheet mounted across the top of the furnace to be heated thereby; and means for spraying water onto said crown sheet for generating steam to form a steam bath within the compartment.
- 20 9. A combination bath apparatus comprising a structural iron frame adapted to be installed within a compartment; a furnace mounted within the forward bottom portion of the frame, said furnace being formed by plates secured in connection with the frame to form a fire box and an ash box; a heat chamber formed within the upper rearward portion of the frame by plates secured upon the said frame; said chamber communicating with the rearward end of the fire box; a boiler mounted within the heat chamber, said boiler having its forward side forming the front of the heat chamber and having its remaining sides spaced from the plates forming the walls of the chamber whereby the boiler may be heated upon three sides and the bottom by heat from the furnace; a cold water supply tank mounted upon the top of the frame and connected to the boiler to maintain a supply of water therein to be heated; means for delivering water from the boiler and the tank for purposes of washing and bathing; a crown sheet mounted across the top of the furnace to be heated thereby; and means for spraying water onto said crown sheet for generating steam to form a steam bath within the compartment.
- 25 10. 45. A combination bath apparatus comprising a structural iron frame adapted to be installed within a compartment; a furnace mounted within the forward bottom portion of the frame, said furnace being formed by plates secured in connection with the frame to form a fire box and an ash box; a heat chamber formed within upper rearward portion of the frame by plates secured upon the said frame, said chamber communicating with the rearward end of the fire box; a boiler mounted within the heat chamber, said boiler having its forward side forming the front of the heat chamber and having its remaining sides spaced from the plates forming the walls of the chamber whereby the boiler may be heated upon three sides and the bottom by heat from the furnace; a cold water supply tank mounted upon the top of the frame and connected to the boiler to maintain a supply of water therein to be heated; means for delivering water from the boiler and the tank for purposes of washing and bathing; a crown sheet mounted across the top of the furnace to be heated thereby; and means for spraying water onto said crown sheet for generating steam to form a steam bath within the compartment; and a partition mounted along one longitudinal side of the frame and extending across the compartment to exclude steam from one side of the compartment whereby one portion may be heated by dry heat directly from the furnace and boiler and the opposite side heated with steam generated therein to form a steam bath.
- 30 11. In witness whereof we hereunto set our signatures.
- 15 16. MICHAEL TROOTNEFF
JOHN GROMEEKO.
